HAIR CURLER

William Arbuckle, Kitchener, Ontario, Canada

Application August 28, 1943, Serial No. 500,359

7 Claims. (Cl. 132—34)

This invention relates to hair curlers and more particularly to those employing two clamping members and my object is to devise a simple curler of this character which is readily operated to effectively curl a lock of hair from one end to the other thereof and under even tension. Further objects I have in mind will hereinafter appear.

This invention is hereinafter fully described and illustrated by way of example, in the accompanying drawing in which

Fig. 1 is a side elevation, on an enlarged scale of my curler;

Fig. 2 an end elevation of the parts shown in Fig. 1;

Fig. 3 a longitudinal section, on the same scale as Fig. 1;

Fig. 4 a perspective view, also enlarged, of the curler; and

Fig. 5 a cross section on the line 5—5 in Fig. 1.

In the drawing like numerals of reference indicate corresponding parts in the different figures.

1 is a hollow mandrel which may be made of any suitable material such as plastic or thin metal and which may be perforated or slotted as indicated at 2. The mandrel may be slightly tapered longitudinally and is provided with a pair of transversely spaced apart lugs 3 having open bearings 4. A rectangular opening 5 is formed in the mandrel between the lugs 3.

An inner clamping member 6 has an outward projection 7 carrying a pivot pin 8, the ends of which form trunnions which are journaled in the open bearings 4. The clamping member is also provided with an inward extension 9 which passes through the opening 5 for engagement by a spring 10 which tends to move the member into clamping engagement with the mandrel 1. The outer end of the projection 7 is serrated for engagement by a finger of the operator's hand to rock the clamping member on its pivot 8 to open said clamp. The member 6 may also be perforated or slotted as indicated at 11.

A knurled or serrated disc 12 is provided with a hub 13 received in one end of the mandrel 1 and secured thereto by means of a pin 14. The pin is flush with the outside periphery of the mandrel on which a collar 15 is rotatably and axially mounted. On the collar is pivoted at 16 an outer clamping member 17, which tapers in thickness towards the free end thereof.

The free end 18 of the outer clamping member 17 has a ball and socket frictional engagement with a spindle 19 for releasably locking the outer clamp 17 in its operative position. The socket is

formed by recessing the end 18 at 20 to receive the semi-spherical ball 21 carried by or formed on the end of the spindle 19. Preferably the ball 21 is formed of resilient material suitably secured to a cup-shaped retainer 22 slidably mounted within the hollow mandrel 1. The retainer 22 is carried by the spindle 19 which extends longitudinally of the mandrel through a bore in the hub 13. The spindle is provided with an elongated slot 23 for the passage of the pin 14 and to permit a limited axial movement of the spindle relative to the pin 14.

The inward extension 9 on the inner clamping member 6 is provided with a hole or slot 24 through which the spindle 19 is passed to limit the outward movement of the trunnions 8 in the open bearings 4. The hole or slot 24 is of sufficient size to permit the member 6 to rock on its pivot 8 even should the pivot be shifted outwardly in its open bearings 4 which occurs when the ends of the lock of hair are clamped adjacent the trunnions 8.

On the spindle 19 is disposed the coil spring 10 which tends to move the ball 21 to lock the outer clamping member 17 in its operative position and tends to rock the inner clamping member 6 to its operative position to clamp a lock of hair between it and the mandrel 1. One end of the spring 10 engages the retainer 22 and the other end engages the extension 9 or a washer 26 interposed between the end of the spring and the extension so that the retainer, ball 21 and spindle 19 are moved in a direction opposite that imparted to the extension 9. Since the inner clamping member 6 is one arm of a bell crank and the extension 9 the other arm thereof, the movement of the extension, by the spring 10, tends to urge the member 6 towards the mandrel 1. When the outer clamp 17 is swung to an inoperative position, the axial movement of the spindle 19 is limited by the engagement of the end of the slot 23 with the pin 14 so that the inner clamping member 6 will still be rocked, by the spring 10, to its operative position.

With the possible exception of the ball 21 and spring 10 all the parts of the hair curler may be made of plastic material. The end of the spindle 19 remote from the ball 21 is provided with a knob 26 whereby the spindle 19 may be manually moved axially against the compression of the spring, to facilitate the disengagement of the ball from the recess 20.

The method of applying my curler is as follows. The outer clamping member 17 is released from the ball 21 and swung out of the way to permit

the free end of a lock of hair or of a group of hairs to be clamped between the inner clamping member 6 and the mandrel 1. The hair is wound around the outer peripheries of the mandrel and clamp 6 by revolving the curler towards the scalp. This operation may be accomplished by turning the disc 12 so that the mandrel 1 and clamp 6 will turn relative to the outer clamp 17, or by holding the clamp 17 and directly engaging the mandrel 1 and clamp 6 to turn them relative to the clamp 17. The collar 15 (and thus the outer clamp 17) is then rotated on the mandrel 1 to enable the outer clamping member 17 to be locked in its closed position to clamp the wound hair close to the scalp. Thus the lock of hair is fully curled, from one end to the other, under even tension throughout the length thereof.

It will be understood that various modifications may be readily made without departing from the spirit of my invention.

What I claim as my invention is:

1. A hair curler comprising a hollow mandrel; means for clamping the free ends of a group of hairs on said mandrel, the said means comprising a bell crank having a slidable pivotal connection with the mandrel, the bell crank having one arm co-operating therewith to form the clamp, the mandrel having an opening for the passage therethrough of the other arm of the bell crank; and a spring in the hollow mandrel for engaging the last mentioned arm to urge the first mentioned arm to its co-operative position with the mandrel, the sliding connection permitting the first mentioned arm to move in and out relative to the mandrel adjacent the pivotal connection.

2. A hair curler comprising a hollow mandrel having a pair of spaced apart lugs extending outwardly therefrom; open bearings in said lugs, the mandrel having an opening between said lugs; means for clamping the free ends of a group of hairs on said mandrel, the said means comprising a bell crank having a slidable pivotal connection in the open bearings and having one arm co-operating with the mandrel to form the clamp, the other arm of the bell crank extending through the opening; and a spring in the hollow mandrel for engaging the last mentioned arm to urge the first mentioned arm to its co-operative position relative to the mandrel, the open bearings permitting the first mentioned arm to move in and out relative to the mandrel adjacent the pivotal connection.

3. A hair curler comprising a hollow mandrel around which a group of hairs may be wound; a clamping member rotatably mounted on the mandrel and swingable relative thereto to clamp the group of hairs adjacent the scalp; means for frictionally retaining the clamping member in its operative position, the retaining means including a spindle axially movable in the hollow mandrel; a ball carried by the spindle; a socket carried by the clamping member adapted to be frictionally engaged by the ball; a coil spring disposed on the spindle for urging the ball into engagement with the socket; and means for limiting the axial movement of the spindle in either direction.

4. A hair curler comprising a hollow mandrel; means for clamping the free ends of a group of hairs on said mandrel, the said means comprising a bell crank pivoted on the mandrel and having one arm co-operating therewith to form the clamp, the mandrel having an opening for the passage therethrough of the other arm of the bell crank; a clamping member rotatably mounted on the mandrel and swingable relative thereto to clamp the group of hairs adjacent the scalp; an axially movable spindle passed through the said hole in the bell crank and having a slot therein; a ball carried by the spindle and slidable in the mandrel; a socket carried by the clamping member adapted to be frictionally engaged by the ball; a coil spring disposed on the spindle for urging the ball and the last mentioned arm in opposite directions to frictionally retain the clamping member in its operative position and tend to rock the first mentioned arm to clamping position.

20

5. A hair curler constructed as set forth in claim 4 in which a disc is secured to the mandrel for rotating the clamping means relative to the clamping member; and a pin is passed through the mandrel and the slot for securing the disc and for limiting the axial movement of the spindle in either direction.

6. A hair curler comprising a hollow mandrel; means for clamping the free ends of a group of hairs on said mandrel, the said means comprising a bell crank pivoted on the mandrel and having one arm co-operating therewith to form the clamp, the mandrel having an opening for the passage therethrough of the other arm of the bell crank; a clamping member rotatably mounted on the mandrel and swingable relative thereto to clamp the group of hairs adjacent the scalp; a spindle; a ball carried by the spindle and slidable in the mandrel; a socket carried by the clamping member adapted to be frictionally engaged by the ball; a coil spring disposed on the spindle for urging the ball and the last mentioned arm in opposite directions to frictionally retain the clamping member in its operative position and tend to rock the first mentioned arm to clamping position.

7. A hair curler comprising a hollow mandrel; means for clamping the free ends of a group of hairs on said mandrel, the said means comprising a bell crank pivoted on the mandrel and having one arm co-operating therewith to form the clamp, the mandrel having an opening for the passage therethrough of the other arm of the bell crank; a clamping member rotatably mounted on the mandrel and swingable relative thereto to clamp the group of hairs adjacent the scalp; a spindle; a ball carried by the spindle and slidable in the mandrel; a socket carried by the clamping member adapted to be frictionally engaged by the ball; a coil spring disposed on the spindle for urging the ball and the last mentioned arm in opposite directions to frictionally retain the clamping member in its operative position and tend to rock the first mentioned arm to clamping position; and means for limiting the axial movement of the ball in the direction for engagement with the socket so that the first mentioned arm will be constantly urged to clamping position.
